(57) **CLAIM**

The ornamental design for a vital sign sensor, as shown and described.

DESCRIPTION

FIG. 1 is an isometric view of a vital sign sensor;
FIG. 2 is a front elevation view of the vital sign sensor;
FIG. 3 is a rear elevation view of the vital sign sensor;
FIG. 4 is a left side elevation view of the vital sign sensor;
FIG. 5 is a right side elevation view of the vital sign sensor;
FIG. 6 is a bottom plan view of the vital sign sensor; and,
FIG. 7 is a top plan view of the vital sign sensor.
The broken lines are included for the purposes of illustrating
unclaimed portions of the vital sign sensor and form no part of
the claimed design.

1 Claim, 3 Drawing Sheets

FIG. 4

FIG. 3
